(57) CLAIM

The ornamental design for a combined wig and head covering, as shown and described.

DESCRIPTION

FIG. 1 is a front elevational view of a combined wig and head covering showing my new design;

FIG. 2 is a rear elevational view thereof;

FIG. 3 is an environmental right side elevational view with the left side being a mirror image thereof; and,

FIG. 4 is a top view thereof.

The broken lines showing a human figure in FIG. 3 are for illustrative purposes only and do not form part of the claimed design.
